UNITED STATES PATENT OFFICE.

HENRY GINSBURG, OF NEW YORK, N. Y., ASSIGNOR TO ROACH-APPLETON MANUFACTURING COMPANY, OF CHICAGO, ILLINOIS, A CORPORATION OF ILLINOIS.

OUTLET-BOX SUPPORT.

Application filed February 20, 1926. Serial No. 89,607.

This invention relates to improvements in electrical apparatus and has reference particularly to outlet boxes and supports therefor commonly used in connection with electric light installations in buildings.

It is desirable in electrical installations of this character to be able to adjust the outlet boxes after their supports are in position and further having made the outlet box fast to the support to insure against rotary movement of the box when the hickey of the lighting fixture is adjusted.

With the foregoing in mind it is the purpose of my invention to provide an outlet box of the character described which may be supported and adjusted on a bar forming the foundation of the box and which when locked to the bar may not be rotated. I accomplish this purpose by means of a simple, cheap and efficient device for expediting the installation of outlet boxes.

The invention is illustratively exemplified in the accompanying drawings, in which, Figure 1 is a top plan view of my improved outlet box and means for connecting same to the supporting bar; Figure 2 is a longitudinal sectional view taken through the same; and Figure 3 is a perspective view of the connecting member. Figure 4 is a transverse sectional view of a modification of the connecting member.

Referring to the drawings, 10 denotes a flat bar hanger of steel or iron which is adapted to be attached to the joists, beams or the like used in building construction and which is provided with perforations 11 to receive the means used to attach the bar to the joists, etc. The outlet box 12 in the present case comprises a cup shaped cast member having a top wall 13 and marginal depending skirt portions 14. Opposite portions of the skirt 14 are straight and form one of the sides of cable chambers 15 which are arranged in pairs at opposite sides of the center of the box. As illustrated clearly in Figure 1 the inner walls of each pair of chambers 15 form an inverted V-shaped corner 16 which is directly opposed to a similar corner of the other pair. The chambers 15 project to a depth corresponding with the length of the skirt 14 and as a consequence the center portion of the box is also depressed forming a central chamber 17. The walls of the central chamber 17 preferably converge slightly towards the bottom,

so as to bring the corners 16 into closer proximity with each other at the bottom across the chamber. Projecting beyond the plane of the skirt 14 and integral with the walls of the central chamber 17 is a threaded projection 18 having an axial bore 19, countersunk at its outer end to accommodate the head of a machine screw 20, the stem 21 of the screw being arranged in the bore 19.

To lock the outlet box 12 on the bar 10, the present invention comprehends a U-shaped strap member 22 having its upright arms 23 provided with slots 24 to accommodate the bar 10 therethrough and below the slots 24 the sides of the arms taper inwardly to meet the bridge portion 25, which is provided at its opposite ends beyond the narrow portion of the arms 23 with V-shaped projections or teeth 26, the latter being adapted to seat in the corners 16 of the center chamber 15 of the outlet box. A threaded opening 27 is provided in the mid portion of the bridge 25 to accommodate the machine screw 20, which when tightened tends to draw the member 22 into the central chamber 15 and since the box 22 rests against the bar 10, adjustment to tighten the screw 20 causes the bar and box to be drawn together. Because of the teeth 26 engaging the corners 16, the box during installation is prevented from turning relative to the bar 10 even before the screw 20 is tightened, thereby enabling the electrician to adjust the box on the bar without losing its position. After the outlet box is tightened to the bar 10 and the electrical connection made, the usual hickey may be adjusted over the threaded projection 18 without fear of the box turning with the hickey.

Another important advantage of the construction herein described lies in the fact that when the fixture is to be removed from the box, the removal may be effected without the box itself turning or becoming substantially loosened from its support. Turning of the box is prevented by the angular projections 26 taking into the orifices 16, these parts having a snug interengagement.

It is within the purview of my invention to modify the form of the connecting member which, instead of being U-shaped as shown in Figure 3 may be in the form of a closed loop, as shown in Figure 4 with the bottom wall of double thickness. The advantage of this modified construction is that

a greater threaded area is presented for engagement by the threads of the screw 21.

What I claim and desire to secure by Letters Patent is:—

1. The combination of a bar hanger of the character described, a carrier strap apertured to receive the bar therethrough and having a projecting portion below the aperture, an outlet box having a hollow screw threaded projection to provide a well to receive the lower portion of the strap, the said lower portion and well being of a shape to prevent relative turning movement of the outlet box and strap, and means extending through and engaging the hollow screw threaded portion and adjustable in the lower portion of the strap to move the latter to clamp the box against the bar.
2. The combination of a bar hanger of the character described, a U-shaped carrier strap apertured adjacent the free ends to receive the bar therethrough and having the closed end of the strap provided with a threaded opening, an outlet box having a hollow screw threaded projection to provide a well to receive the closed end of the strap, the latter having opposite projections to fit depressions in the wall of the well to prevent relative turning movement of the box and bar, and a screw extending through and engaging the hollow screw threaded portion and adjustable in the threaded opening in the strap to move the latter to draw the box against the bar.

In testimony whereof I affix my signature.

HENRY GINSBURG.

CERTIFICATE OF CORRECTION.

Patent No. 1,639,496.

Granted August 16, 1927, to

HENRY GINSBURG.

It is hereby certified that the above numbered patent was erroneously issued to Roach-Appleton Manufacturing Company, of Chicago, Illinois a corporation of Illinois, as assignee, whereas said patent should have been issued to the inventor said Ginsburg, as owner of the entire interest in said invention; and that the said Letters Patent should be read with this correction therein that the same may conform to the record of the case in the Patent Office.

Signed and sealed this 4th day of October, A. D. 1927.

Seal.

M. J. Moore,
Acting Commissioner of Patents.
